UNITED STATES PATENT OFFICE.

WILLIAM SHERMAN VAN SANT AND EDMOND CURTIS EAMES, OF DIXON,
CALIFORNIA.

COIN-ACTUATED LIQUID-VENDING MACHINE.

SPECIFICATION forming part of Letters Patent No. 441,861, dated December 2, 1890.

Application filed June 24, 1890. Serial No. 356,544. (No model.)

To all whom it may concern:

Be it known that we, WILLIAM SHERMAN VAN SANT and EDMOND CURTIS EAMES, citizens of the United States, residing at Dixon, 5 Solano county, State of California, have invented an Improvement in Coin-Actuated Liquid-Vending Machines; and we hereby declare the following to be a full, clear, and exact description of the same.

Our invention relates generally to the class of machines adapted to deliver an article upon the deposit of a suitable coin.

Our invention consists in the machine of this class which is hereinafter fully described, 15 and its novel features of construction, combination, and arrangement specifically pointed out in the claims.

The object of our invention is to provide a machine containing one or more beverages, a 20 tumblerful of any one of which will be delivered to the customer upon the deposit by him of the proper coin.

Referring to the accompanying drawings for a more complete explanation of our invention, Figure 1 is a perspective view of our 25 machine. Fig. 2 is a vertical section on line $x-x$ of Fig. 1. Fig. 3 is a vertical section on line $y-y$ of Fig. 1. Fig. 4 is a view showing the circuits and connected parts.

A is the case or box which forms the frame of the machine. This is divided by a horizontal partition B into a top chamber a , below which is a second chamber a' , having a floor b , under which is a third compartment 35 or chamber a^2 , which is divided from the lowest chamber or base of the box by a partition b' .

In the walls of the chambers a and a' are let panes of glass C, whereby the interior of 40 said chambers may be seen. The panes should preferably be doubled to exclude the warmer outer air and confine the inner colder air.

Within the uppermost compartment or chamber a are the liquid-vessels D in any suitable number, according to the different liquids or beverages which the machine is adapted to vend. For convenience, we have here shown but two, one of which may be supposed to contain one form of beverage—such,

for example, as lemonade—and the other a different beverage—as, for example, soda-water. These vessels D may be in any suitable shape. (Here shown as having somewhat the shape of bottles or demijohns inverted.)

55

Communicating with their bases and extending downwardly into the chamber a' are the discharge-pipes d, by which the liquids from said vessels are conveyed downwardly, and also extending downwardly from the bases of said vessels are air-pipes d', the lower ends of which terminate short of the lower ends of the pipes d.

Within the chamber a' are the tilting measuring-cups E, into which the discharge-pipes d extend, reaching well down within said cups. The air-pipes d' also extend down into said cups, their lower ends terminating at the level to which it is desired to fill the cups. It will now be seen that the liquid from vessels D 70 will pass down into the measuring-cups and rise within said cups to just above the level of the lower ends of the air-tubes d', and the air being thus cut off, the liquid will remain at this level in said cups, and when the cups 75 are emptied will again flow down and rise to this level. There is, therefore, always in said cups a measure of liquid ready to be discharged. The measuring-cups are supported upon the outer ends of arms F, which are pivoted at f in the tops of standards f', said standards being vertically adjustable in bearings f², and set in position by set-screws f³, and by the adjustment of these standards the position of the measuring-cups with relation 80 to the pipes d and d' is regulated.

Adjustable weights W are fitted upon the outer ends of the arms F, and serve as counter-balances. The arms are held horizontally to hold the measuring-cups in position by means of a catch hereinafter described. The measuring-cups E lie within the upper ends of the funnels G, the necks g of which extend downwardly through the floor b, as shown.

Within the compartment a^2 and extending downwardly into the base of the box are casings H, in the lower portions of which are springs h. Upon these springs are mounted the series of tumblers I, the upper tumblers 90

95

100

of said series being within the compartment a^2 and directly below the necks g of the discharge-funnels G . Access is had to the uppermost tumbler of the series through proper openings a^3 in the wall of compartment a^2 , so that the hand may be passed through said openings into the casings H , and the uppermost tumbler removed.

The operation of these parts is as follows. Within the compartment a' is placed suitably a body of ice J , and the partition B is provided with apertures b^2 , thus effecting a communication between the chambers a and a' , whereby the air within said chambers and the beverages are kept cool. As before stated, a portion of the liquid is within the measuring-cup. Now upon releasing the arm F the cup will tilt about the pivotal center f and discharge its contents into the funnel G , and the liquid will run down through the neck of the funnel into the uppermost tumbler, and will sufficiently fill said tumbler, this being regulated by the capacity of the measuring-cup. The uppermost tumbler being now removed by the customer, the series of tumblers is raised by the spring, so that a fresh tumbler is ready to receive the next measure of liquid. The series of tumblers is held in place by means of a stop i , against which the uppermost tumbler comes in contact. In the upper portion of the box or case is the slot K , through which the proper coin is to be inserted. From this slot extends inwardly a coin-passage k , the inner end of which is just above a tilting coin-tray L , which receives the coin from said passage. The coin-passage is a flattened partial tube receiving the coin edgewise, so that said coin will readily run down. This tray is on the outer end of a lever l , which is pivoted to a suitable standard at l' , and has a weight W' upon its rear end, whereby the tilting tray is held up normally to receive the coin. The weight W' is just sufficient to hold the tray in this position when there is no coin upon it; but when a coin drops upon the tray the weight is overcome and the lever l rocks. Within the base of the case is an electric battery M . Within compartment or chamber a' are electro-magnets N , each having a pivoted armature n , controlled by a spring n' , and having its upper end formed with a catch n^2 , which engages the outer end of the arm F , thereby holding said arm horizontally and holding the cup which said arm carries. The spring n' holds the catch normally to its engagement with the arm F . There is one of these electro-magnets and one armature-catch for each arm F . Suitable circuit-wires pass from the battery, and include the electro-magnets. Now, when the circuit is closed, the electro-magnet being energized, attracts its armature, thereby releasing the catch n^2 from the arm F , and allowing the cup by the weight of its contents to tilt and discharge its liquid. When emptied, the weight W returns it to position and another portion of liquid descends automati-

cally from the vessel D above into the cup. The circuit being now open the armature is not attracted by the magnet, and its spring n' throws the catch n^2 back again to its engagement with the arm F , whereby the cup is held. The circuit is closed and opened by electrode O on the vibrating lever l and electrode o . These are normally separate, but when the coin-tray is depressed by the weight of the coin the electrode O comes into contact with electrode o , thereby closing the circuit. The coin is discharged by the tilting of the tray L into a suitable receptacle P , and thereupon the weight W' returns the tray and opens the circuit at O o . Now where the machine contains different beverages it is necessary to provide means whereby the purchaser may obtain the one he desires. This is done by providing a switch or key-board to throw any one of the electro-magnets into or out of the circuit. This we have shown at Q , which is a key-board having suitable independent contacts, and a removable key q , adapted to be inserted in the board and to close the proper electro-magnet circuit. Thus one or the other of the circuits is closed, and the particular magnet of that circuit is thereby operated to trip the catch and allow the proper measuring-cup to tilt and deliver the liquid chosen.

In order to avoid the use of any piece of metal as a key, we let our key q into the circuit by attaching it to a wire or preferably a flexible steel tape q' , Fig. 4, which forms part of the circuit.

R is a drip-pan to catch any waste there may be.

Having thus described our invention, what we claim as new, and desire to secure by Letters Patent, is—

1. In a coin-actuated liquid-vending machine, the combination of a liquid-vessel, a tilting measuring-cup below adapted to receive the liquid from said vessel, a discharge-funnel to receive the contents of the cup, and a coin-actuated catch for holding and tripping said cup, substantially as herein described.

2. In a coin-actuated liquid-vending machine, the combination of a liquid-vessel, a tilting measuring-cup below, into which the liquid is conveyed from the vessel, a discharge-funnel to receive the contents of the measuring-cup, and an electrically-operated catch for holding and tripping the tilting cup, substantially as herein described.

3. In a coin-actuated liquid-vending machine, the combination of a liquid-containing vessel, a tilting measuring-cup below receiving the liquid from said vessel, a discharge-funnel into which the liquid is delivered from the cup, a catch for holding and releasing the cup, an electric circuit and connections for operating the catch, and a circuit closer and opener operated by a deposited coin, substantially as herein described.

4. In a coin-actuated liquid-vending ma-

chine, the combination of a liquid-vessel above, a tilting measuring-cup connected with the liquid-vessel and adapted to receive the liquid therefrom, a discharge-funnel for receiving the liquid from the tilting-cup, a tumbler-casing into which the neck of the discharge-funnel extends, whereby its contents are delivered to the tumbler, a catch for holding and tripping the tilting measuring-cup, an electric circuit and connections for operating the catch, and a circuit closer and opener operated by the deposited coin, substantially as herein described.

5. In a coin-actuated liquid-vending machine, the combination of separate liquid-containing vessels, tilting measuring-cups below and connected one with each vessel, a discharge-funnel for each cup receiving the liquid therefrom, independent catches for holding and tripping the cups, electric circuits and separate connections for operating each catch independently, a circuit closer and opener operated by the deposited coin, and a key-board or switch for opening and closing 25 the circuits independently to affect any one of the catches, whereby any one of the measuring-cups may be tripped, substantially as herein described.

6. In a coin-actuated liquid-vending machine, the combination of the liquid-vessel above, the tilting measuring-cup below, the automatic connection between the vessel and cup, consisting of the downwardly-extending liquid-pipe and air-pipe, the discharge-funnel which receives the liquid from the tilting-cup, a catch for controlling said cup, an electric circuit and connections for operating the catch, and a circuit closer and opener operated by the deposited coin, substantially 10 as herein described.

7. In a coin-actuated liquid-vending machine, the combination of a liquid-vessel, a tilting measuring-cup below communicating therewith, and a discharge-funnel to receive 5 the liquid from said cup, the pivoted counterbalanced arm upon which said cup is mounted, the electro-magnet and the armature of said magnet having the catch engaging the arm of the cup, an electric circuit including the magnet, and a circuit closer and opener operated by the deposited coin, substantially as herein described.

8. In a coin-actuated liquid-vending machine, the liquid-vessel, the tilting measuring-cup below connected therewith, and the discharge-funnel into which the measuring-cup delivers its contents, in combination with an electrically-operated catch for holding and tripping the measuring-cup, and the circuit closer and opener consisting of the coin-receiving tray L, the pivoted counterbalanced lever l, and the electrodes O and o of the electric circuit, substantially as herein described.

9. In a coin-actuated liquid-vending ma-

chine, the combination of the liquid-vessel, 65 the tilting measuring-cup below and connected therewith, the discharge-funnel for receiving the liquid from the measuring-cup, the pivoted counterbalanced arm carrying the measuring-cup, the armature having a catch 70 engaging the arm, the electro-magnet affecting the armature, an electric circuit including the magnet, the vibrating coin-receiving tray L, the counterbalanced pivoted lever carrying the tray, and the electrodes O and o of the 75 electric circuit, substantially as herein described.

10. A coin-actuated liquid-vending machine consisting of a box or case having a compartment a in its top, a compartment a' 80 thereunder and communicating with the upper compartment, and a compartment a² below, a liquid-vessel in the uppermost compartment, a tilting measuring-cup in the compartment a', liquid and air pipes connecting 85 the vessel above with the measuring-cup, whereby it is automatically supplied, a discharge-funnel into which the measuring-cup delivers its contents, said funnel having a neck extending downwardly into the compartment a², a casing for containing the tumblers below the discharge-neck of the funnel, and having a spring by which the series of tumblers is fed upwardly, an opening from the exterior into compartment a², whereby the 95 tumblers may be reached, the pivoted counterbalanced arm carrying the measuring-cup, the electro-magnet having an armature with a catch for holding and tripping the arm of the measuring-cup, an electric battery in 100 the base of the case or box, an electric circuit including the electro-magnet, a coin-passage having a slot at its outer end, a tray for receiving the coin at the inner end of said passage, the vibrating counterbalanced lever carrying the tray, and the electrodes O and o of the 105 electric circuit, substantially as herein described.

11. In a coin-actuated liquid-vending machine, the combination of separate liquid-vessels, a tilting measuring-cup for each vessel, a discharge-funnel for each cup, a catch for holding and tripping each cup, electric circuits and connections for controlling each catch, a circuit closer and opener operated by 115 the deposited coin, a key-board or switch let into the circuits and having independent contacts, and a removable key let into the circuits and adapted to close and open them independently at the key-board, substantially as 120 herein described.

In witness whereof we have hereunto set our hands.

WILLIAM SHERMAN VAN SANT.
EDMOND CURTIS EAMES.
